United States Patent Office

Des. 186,609
Patented Nov. 10, 1959

186,609

GAME BOARD

Lawrence R. Beebe, Portland, Oreg.

Application May 11, 1959, Serial No. 55,860

Term of patent 7 years

(Cl. D34—5)

Fig. 1

Fig. 2

Figure 1 is a top plan view of a game board showing my new design.

Figure 2 is a side elevational view of Figure 1.

I claim:

The ornamental design for a game board, substantially as shown.
